(57) **CLAIM**

The ornamental design for a mobile terminal holster, as shown and described.

DESCRIPTION

FIG. 1 is a front, right and top perspective view of a mobile terminal holster showing our new design;

FIG. 2 is a rear view thereof;

FIG. 3 is a front view thereof;

FIG. 4 is a right view thereof;

FIG. 5 is a left view thereof;

FIG. 6 is a top view thereof;

FIG. 7 is a bottom view thereof; and,

FIG. 8 is another front, right and top perspective view thereof without dotted or broken lines.

The broken lines shown in FIGS. 1–7 are included for the purpose of illustrating environmental elements only and form no part of the claimed design.
